PREPARATION OF TOCOPHEROLS

Frank J. Sevigne, Tarrytown, N.Y., assignor, by mesne assignments, to General Mills, Inc., Minneapolis, Minn., a corporation of Delaware
No Drawing. Filed Aug. 28, 1961, Ser. No. 134,142
The portion of the term of the patent subsequent to Aug. 29, 1978, has been disclaimed
7 Claims. (Cl. 260—345.5)

This application is a continuation-in-part of Serial No. 763,450, filed September 26, 1958, now U.S. Patent No. 2,998,430, issued August 29, 1961.

This invention relates to a process for the conversion of tocopherol compounds from non-useful mixture to a biologically useful condition and, in particular, is concerned with the conversion of tocopherol isomers to useful alpha form.

As is well known, alpha tocopherol has high vitamin E activity, while non-alpha tocopherols, such as beta, gamma and delta, have much lower activity. Since the non-alpha forms predominate in nature many attempts have been made to convert them to the more biologically active alpha form. The non-alpha tocopherols differ from the alpha only in that one or both methyl groups are missing from the 5-7 positions. Attempts at conversion in the past have involved the direct methylation of the non-alpha tocopherols and have been reasonably successful.

This invention provides a method for the conversion of non-alpha tocopherol compounds to the alpha form, which is characterized by a sequence of steps comprising, first, oxidizing the compounds to quinone form and opening the chroman ring, reducing said quinone form to hydroquinone, thereupon haloalkylating the said compounds, then reclosing the ring to give the desired alpha tocopherol. The process is thus characterized by the sequence and combination of steps involved in the process, all of which are carried out under very mild conditions, which result in minimum formation of impurities and side reactions, the process being further characterized by the smoothness and ease with which it takes place in each step and the high yields obtained at each step in the operation.

The process of the present invention may be carried out with non-alpha tocopherols in various forms. It may be carried out with the various pure non-alpha tocopherols, i.e., β , γ , δ , or it may be carried out with impure mixtures of inert materials containing varying, even small, amounts of the tocopherols or tocols. For instance, it may be carried out with by-products resulting from the refining of vegetable oils. Hot well sludge from the steam refining of vegetable oils, soybean oil, corn oil, wheat germ oil, peanut oil, cottonseed oil and the like, are sources of the deodorizer sludge. Wheat carries variable but significant amounts of the tocopherol compounds. A summary of the variants of tocopherol and the tocols to which the process is applicable is found in British Patents 809,895 and 827,391, which disclosures are fully incorporated herein. It will be understood that the several steps of the invention may be carried out in different ways with different raw materials and under modified conditions to suit the particular raw material being processed.

In summary, therefore, the process may be illustrated by the following sequence of reactions.

EXAMPLE I

Chloromethylation of pure γ -tocopherol hydroquinone

(a) PREPARATION OF γ -TOCOPHERYL HYDROQUINONE

Ten grams (10.0 g.) of γ -tocopherol

($E_{1\text{cm.}}^{1\%}$, 297 mg.=92.4)

having a purity of 99.1% as determined by the Emmerie-Engel assay were dissolved in 210 ml. of ethyl alcohol.

2

To this solution was added 25 grams of $\text{FeCl}_3 \cdot 6\text{H}_2\text{O}$ dissolved in 180 ml. of ethyl alcohol. The mixture was stirred for 10 minutes at room temperature and then refluxed for an additional ten minutes. The mixture was cooled, 1000 ml. of water were added and the aqueous mixture extracted successively with 600 ml., 400 ml. and 400 ml. portions of ethyl ether. The combined ethyl-ether solutions were washed five times with 400 ml. portions of distilled water, dried over anhydrous sodium sulfate, and the solvent removed under vacuum. A reddish-yellow oil was obtained as a residue (10.2 gms.) having

$E_{1\text{cm.}}^{1\%}$, 260 $\mu\text{m.}$ =314

The γ -tocopherol quinone (10.0 gms.) was taken up in 100 ml. of methanol and placed in a hydrogenation apparatus and hydrogen bubbled through in the presence of Raney nickel as a catalyst for 1 hour. The catalyst was filtered off; the methanol solution diluted with 200 ml. of water, and then extracted successively with three 200 ml. volumes of ethyl ether. The combined ether extracts were washed three times with 200 ml. portions of water, dried with sodium sulfate and the ethyl ether removed under vacuum. The resulting γ -tocopherol hydroquinone (8.9 gms.) assayed 94% pure by the Emmerie-Engel assay.

The above described reaction, extraction and washing steps were done under subdued light to prevent distribution of the sensitive quinone and hydroquinone compounds. In the reduction of gamma tocopherol quinone to gamma-tocopherol hydroquinone, the following reducing substances can be used: (1) alkali metal hydrosulphites such as potassium hydrosulphite and sodium hydrosulphite; (2) the alkali metal hydrides and borohydrides such as lithium aluminum hydride, sodium borohydride, and potassium borohydride; (3) hydrogen gas in the presence of a suitable hydrogenation catalyst, such as palladium on a carbon or calcium carbonate carrier, Raney nickel, etc.

For the oxidation of gamma tocopherol to gamma tocopherol quinone, the following oxidizing agents are satisfactory: ferric chloride, gold chloride, silver nitrate and ceric sulphate.

(b) CHLOROMETHYLATION OF γ -TOCOPHERYL HYDROQUINONE

Gamma-tocopherol hydroquinone (8.34 gms.) was dissolved in 115 ml. of anhydrous ethyl ether. Chloromethyl ether (2.25 ml.) was added and the ether solution refluxed for 1½ hours. The chloromethyl ether and ethyl ether were removed under vacuum yielding a dark reddish oil (8.59 gms.). When a sample of this oil was fused with sodium metal, a positive test for chloride ion was obtained with silver nitrate solution.

(c) REDUCTION OF CHLOROMETHYLATED γ -TOCOPHERYL HYDROQUINONE

6.37 gms. of the gamma tocopherol chloromethylated hydroquinone was dissolved in 50 ml. of ethyl ether. 10.5 ml. of 36% HCl was added and to the mixture, 3.6 gms. of zinc dust was slowly added and the reaction allowed to proceed for one hour. The ether layer was separated, washed with water until chloride free, dried with anhydrous sodium sulfate, and the ether evaporated under vacuum to yield a light yellow oil (6.10 gms.). Fusion of a sample of oil with sodium metal and treatment with AgNO_3 solution gave a negative test for chloride ion.

(d) CYCLIZATION WITH STANNOUS CHLORIDE

6.0 gms. of the reduced hydroquinone was dissolved in 35 ml. of 1,4 dioxane; 3.55 gms. of $\text{SnCl}_2 \cdot 2\text{H}_2\text{O}$ and 5 ml. of 36% HCl were added and the mixture refluxed for 7½ hours at 92° C. The mixture was cooled to room temperature, 100 ml. of water added and the aqueous mixture extracted with 20 ml., 30 ml. and 35 ml. portions of petroleum ether. The petroleum ether solution was

washed five times with 60 ml. portions of distilled water, dried with sodium sulfate, and the petroleum ether removed under vacuum. A light orange oil (5.7 gms.) was obtained which assayed 68% total tocopherols of which 91% was in the form of alpha-tocopherol. The chemical structure was further proved by conversion to the acid succinate ester which gave a product melting at 76.5° C., identical with that of alpha tocopheryl acid succinate.

EXAMPLE II

Chloromethylation of beta-tocopheryl hydroquinone

0.1 gm. of pure beta-tocopherol was dissolved in 5 ml. of methyl alcohol. A solution containing 0.25 gm. of $\text{FeCl}_3 \cdot 6\text{H}_2\text{O}$ in 5 ml. of methyl alcohol was added dropwise over a period of fifteen minutes and the mixture was then refluxed for an additional 5 minutes. The mixture was diluted with 20 ml. of distilled water, cooled to room temperature and extracted with 20 ml., 10 ml. and 10 ml. portions of ethyl ether. The combined ether solutions were washed five times with water, dried with anhydrous sodium sulfate, filtered and the solvent removed under vacuum. The residue consisted of a reddish-yellow oil.

The beta-tocopheryl quinone (0.08 gm.) was suspended in 5 ml. of methyl alcohol and to the mixture was added 0.2 gm. of sodium hydrosulfite in 1 ml. of water. The mixture was shaken for 40 minutes, diluted with 20 ml. of water and extracted twice with 10 ml. portions of ethyl ether. The ether solution of the resulting beta-tocopheryl hydroquinone was dried in the usual manner with sodium sulfate.

To the ethyl ether solution was added 0.2 ml. of concentrated hydrochloric acid and 0.1 gm. of paraformaldehyde. The mixture was stirred under nitrogen for three hours. Two-tenths (0.2) gm. of concentrated hydrochloric acid was added and then 0.25 gm. of zinc dust added slowly over a 30 minute period. The mixture was stirred for an additional period of 1 hour. The mixture was then extracted three times with 10 ml. portions of ethyl ether. The ether extracts were combined, washed four times with 5 ml. portions of distilled water, dried over sodium sulfate, filtered, and the solvent removed under vacuum.

The reduced chloromethylated product (0.55 gm.) was dissolved in 5 ml. of glacial acetic acid. Hydrobromic acid (0.5 ml.) and zinc dust (0.2 gm.) were added and the mixture refluxed for 10 minutes under nitrogen. After diluting with 40 ml. of water, the acid solution was extracted three times with 30 ml. portions of ethyl ether. The combined ether extracts were washed twice with 10 ml. portions of 2 N Na_2CO_3 solution and then six times with 10 ml. portions of distilled water. The ether solution was dried over sodium sulfate, filtered, and the solvent removed under vacuum. The residue consisted of a pale yellow oil containing 57 percent alpha-tocopherol according to chemical assay.

EXAMPLE III

Chloromethylation of delta-tocopheryl hydroquinone

One-tenth (0.1) gm. of pure delta-tocopherol was dissolved in 5 ml. of absolute methyl alcohol. A solution of 0.25 gm. of $\text{FeCl}_3 \cdot 6\text{H}_2\text{O}$ in 5 ml. of methyl alcohol was added dropwise over a period of fifteen minutes. Twenty (20) ml. of distilled water were added and the mixture extracted three times with 20 ml. portions of ethyl ether. The combined extracts were washed five times with 10 ml. portions of distilled water, dried with sodium sulfate, filtered, and the solvent distilled off under vacuum.

The reddish-yellow oil obtained was subjected to a second oxidation under identical conditions. The oxidizing solution was diluted with water and extracted three times with 20 ml. portions of ethyl ether. The combined extracts were washed with distilled water, dried over sodium sulfate, filtered, and the solvent removed under vacuum. The resulting delta-tocopheryl quinone appeared as a red oil.

The quinone (0.09 gm.) was suspended in 8 ml. of methyl alcohol and to the mixture was added 0.2 gm. of sodium hydrosulfite in 1 ml. of water. The mixture was shaken for 30 minutes, diluted with 20 ml. of water and extracted three times with 100 ml. portions of ethyl ether. The ether solution of the resulting delta-tocopheryl hydroquinone was dried in the usual manner with sodium sulfate.

To the ethyl ether solution was added 0.5 ml. concentrated hydrochloric acid and 0.2 ml. Formalin. The mixture was stirred vigorously for two hours under nitrogen.

To the resulting ether solution of the chloromethylated hydroquinone was added 0.4 ml. of concentrated hydrochloric acid and 1.0 gm. of zinc dust was also added over a ten minute period with stirring. The reaction was continued for two hours. The ether layer was decanted from the acid solution and zinc residue, washed ten times with 10 ml. portions of water, dried over sodium sulfate, and the solvent removed under vacuum. The residue consisted of a pale yellow oil (0.088 gm.).

The hydroquinone (0.088 gm.) was dissolved in 2 ml. of dioxane and refluxed for six hours under nitrogen with 0.2 gm. stannous chloride and 0.15 ml. concentrated hydrochloric acid. The mixture was diluted with 10 ml. water and extracted three times with 10 ml. portions of ethyl ether. The combined extracts were washed with water, dried over sodium sulfate, and the ether removed under vacuum.

The resulting yellow oil contained 78% total tocopherols according to chemical assay. The alpha tocopherol content of the oil was 51.7% as indicated by chemical assay.

EXAMPLE IV

Fifteen (15.0) gms. of a mixed tocophenol concentrate having a total tocopherol and non-alpha tocopherol content of 65% and 59% respectively, and prepared from soybean oil deodorizer sludge by the processes of saponification and molecular distillation was treated according to the chemical procedures outlined in Example I. The resulting yellow oil contained 46% total tocopherols by chemical assay. The alpha tocopherol content was 44% as indicated by chemical assay according to the method of Quaife (J. Biol. Chem., 175, 605, 1948).

In the extraction of tocopheryl quinone reaction product in the first stage ethyl ether is used, because that has the advantage of being a good solvent immiscible with water and effective for the purpose. However, other ethers, such as methylethyl ether may be used, because the basic requirement is high solvent capacity for the tocopherol.

In the chloromethylation phase of the operation, the solvent used was ethyl ether in the several examples, but it is to be understood, of course, that any solvent for the reactants would be useful. Here methyl ether or methylethyl ether will serve the purpose. In the actual chloromethylation which is conducted, the formaldehyde and hydrogen chloride may be used in the gaseous form, or the formaldehyde may be used in the solid paraldehyde form. Similarly, the reducing agent is zinc dust and hydrochloric acid because it is a convenient one, but actually any pair of reactants, for example, a zinc amalgam is suitable for forming the nascent hydrogen.

In the cyclization step of reaction, glacial acetic acid hydrochloric acid and zinc dust were used. The reactions were specific but it is to be understood that any reactants usable for the purpose of closing the chroman ring might be used.

Although the invention has been described with reference to a limited number of examples, it is to be understood variations thereof may be practiced without departing from the spirit or scope of the invention.

What is claimed is:

1. The process of converting a tocopherol compound, in a source material extracted from a natural source, to

alpha tocopherol form, comprising, oxidizing said material containing said tocopherol compound whereby the chroman ring opens forming a tocopheryl para quinone, reducing said product to hydroquinone form, chloromethylating said parahydroquinone, whereby any hydrogen atoms present on the phenyl ring are replaced with chloromethyl radicals, reducing said compound whereby the chloromethyl radicals are converted to methyl radicals, and closing the ring of said compound whereby alpha tocopherol is produced.

2. The process of claim 1 wherein the tocopherol compound is a compound selected from the group consisting of beta, gamma, delta tocopherols and mixtures thereof.

3. The process of claim 1 wherein the oxidation step is conducted by reacting the tocopherol with ferric chloride.

4. The process of claim 1 wherein the chloromethylation step is conducted by reacting the hydroquinone with a formaldehyde yielding material and hydrochloric acid.

5. The process of claim 1 wherein the reduction step is conducted by reacting the chloromethylated product with zinc dust and hydrochloric acid.

6. The process of claim 1 wherein the cyclization step is conducted with stannous chloride.

7. The process of claim 1 wherein the cyclization step is conducted with zinc chloride.
